UNITED STATES PATENT OFFICE.

JOZEF MATUSZYK, OF PANA, ILLINOIS.

DRILL-HOLE CHARGER.

Application filed November 5, 1926. Serial No. 146,458.

This invention relates to improvements in drill hole chargers, and has more particular reference to an improved charger for supplying powder to drill holes for blasting.

5 The primary object of the invention is to provide a charger of the above kind which is extremely simple and durable in construction as well as efficient in use.

10 A more specific object of the invention is to provide simple means for enabling the charger to be filled with powder conveniently and safely as well as with facility.

15 Another object of the invention is to provide a charger of the above kind which may be conveniently and safely handled as well as readily placed into use for expeditiously supplying a drill hole with powder for blasting purposes.

20 Other objects will become apparent as the nature of the invention is better understood, and the same consists in the novel form, combination and arrangement of parts hereinafter more fully described, shown in the accompanying drawing and claimed.

25 In the drawing, wherein like reference characters indicate corresponding parts throughout the several views,

30 Figure 1 is an elevational view, partly broken away, of a charger constructed in accordance with the present invention;

35 Figure 2 is a view partly in elevation and partly broken away and in section, illustrating the charger tube operatively associated with a powder container for being filled with powder;

40 Figure 3 is a central longitudinal sectional view of the charger shown in Figure 1, in filled condition, and capped for safe handling;

45 Figure 4 is a view somewhat similar to Figure 3 of the charger, further broken away, and with its outlet cap removed preparatory to insertion of the charger in the drill hole; and

50 Figure 5 is a fragmentary elevational view of the powder container shown in Figure 2, illustrating the means for operatively associating the inlet end of the charger with the powder outlet of the powder container whereby the charge carrying tube of the charger may be filled with safety and without danger of spilling the powder.

55 Referring more in detail to the drawing, the present charger includes a charge receiving tube 5 of relatively long and tapered form and preferably constructed of sheet

metal. The tube 5 tapers smaller gradually from its inlet end to its outlet end so as to facilitate its insertion into the drill hole when charging the latter, and removably applied to the opposite ends of the tube 5 are inlet and outlet closure caps 6 and 7 respectively. These caps 6 and 7 are preferably constructed of sheet metal and are retained in place upon the ends of the tubes 5 by the frictional fit of the same on the latter. The caps 6 and 7 are equipped with suitable loops or handles 8 by means of which the said caps may be conveniently removed when desired, and placed in the smaller outlet end of the tube 5 is a frail or readily destructable plug 9 of paper or the like.

When the tube 5 is filled with powder as indicated in Figure 3, and the caps 6 and 7 are in place upon the ends of the tube, it is evident that the charger may be readily handled with safety and without danger of spilling the powder. When it is desired to charge the drill hole, the cap 7 is removed from the outlet end of the tube 5, whereupon the latter is inserted in the drill hole with the smaller outlet end foremost, the readily destructable plug 9 preventing spilling of the powder after removal of the cap 7. However, upon insertion of the tube 5 completely into the drill hole, the plug 9 will become destroyed through contact with obstructions or projections or by excessive vibration of the charge containing tube 5 so that upon removing the latter from the drill hole the powder will pour out of the tube 5 into the drill hole. However, when found necessary under extraordinary conditions, the dispensing of the powder from the tube 5 may be effected in any suitable manner upon removal of the cap 6 although the latter is not usually necessary and the charging operation is accordingly usually possible with extreme safety or without danger of spilling the powder or igniting the same inadvertently.

In lowering the tube into the drill hole a rope or cord is attached to the loop 8 of the cap 6, it being understood that the cap fits the tube tightly enough to prevent the cap from being displaced by the weight of the filled tube; to remove the cap will of course, require forcible manipulation.

In order to permit filling of the tube 5 conveniently and safely without danger of igniting the powder or spilling the same, I provide a sleeve 10 adapted to slide on the inlet or larger end of the tube 5 with a fric-

tional fit when the cap 6 is removed, and the outer end of the sleeve 10 is provided with a lateral continuous flange 11 adapted to slide into a guideway 12 when the tube 5 is moved laterally with the flange 11 in contact with the outer surface of the wall 13 of a powder container, until the open inlet end of the tube 5 is brought into registry with the outlet opening 14 in said wall 13 of the powder container. In this way the charge containing tube 5 is effectively coupled to the powder container for being filled with powder when said powder container is positioned for the powder to pour therefrom through the opening 14. As shown, the flange 11 and guideway 12 are preferably of rectangular form with the guideway open at one side to admit the flange 11 and closed at the other side to limit the lateral movement of the tube to a position wherein the open end of the latter is registered with the opening 14 of the powder container. By reason of the construction thus described, a tight joint is provided between the end of the tube 5 and the powder container so that spilling of the powder will be prevented during the operation of filling tube 5, and so that accidental ignition of the powder at this time is also prevented. The plug 9 is of course inserted in the smaller lower end of the tube 5 and the cap 7 is applied to said smaller end of tube 5 prior to this filling operation, and

when the tube 5 is completely filled, it is detached from the powder container by sliding the same laterally in the opposite direction to dis-engage flange 11 from guideway 12. The sleeve 10 is then removed from the tube 5 and the cap 6 applied to the latter, whereupon the charger is in condition for convenient handling.

From the foregoing description it is believed that the construction and manner of use as well as the advantages of the present invention will be readily understood and appreciated by those skilled in the art.

Minor changes may be made without departing from the spirit and scope of the invention as claimed.

What I claim as new is:—

A drill hole charger comprising an elongated tapering tube, a fragile plug in the smaller outlet end of the tube, a removable closure for the ends of the tubes, the closure for the upper and larger end of the tube being constructed as a flanged cap embracing the wall of the tube and being provided with a loop forming a handle by which the cap can be manipulated and a means for the attachment of a lowering and lifting cord, said cap being in such tight frictional contact with the tube as to avoid displacement by the weight of the tube.

In testimony whereof I affix my signature.
JOZEF MATUSZYK.
